UNITED STATES PATENT OFFICE

2,293,593

HAIR TREATING APPARATUS

Frederick J. Clark, Buffalo, N. Y., assignor to Albert Shelby, Buffalo, N. Y.

Application July 25, 1941, Serial No. 404,031

6 Claims. (Cl. 132—36)

This invention relates to apparatus for treating live or growing human hair, in which a device for treating or operating upon the hair is mounted on a stand or support by which the treating device can be adjusted and held stationary in different positions enabling it to conveniently and properly operate upon tresses or locks of hair on different portions of the subject's head.

Particular objects of the invention are to provide a practical and desirable apparatus of novel construction, by which the treating device can be quickly and easily adjusted, practically universally, so as to hold it stationary in whatever different positions may be necessary to most efficiently and conveniently treat or operate upon tresses or locks of hair on all portions of the head; to provide an apparatus having means for elevating and lowering the treating device and also adjusting it angularly both horizontally and in different vertical planes at an angle to each other when at the desired elevation in order to set and hold the device in different desired positions relative to different portions of the subject's head.

Further objects and advantages of the invention will appear from the following specification of the preferred embodiment of the invention, shown in the accompanying drawings, and the novel features of the invention are set forth in the appended claims.

In said drawings:

Fig. 1 is a side elevation, on a reduced scale, of a hair treating apparatus embodying my invention.

Fig. 2 is fragmentary, transverse, sectional elevation thereof, on a larger scale, on line 2—2, Fig. 1.

Fig. 3 is a fragmentary front elevation of the apparatus.

Fig. 4 is a sectional plan view thereof on line 4—4, Fig. 1.

Fig. 5 is a longitudinal, sectional elevation thereof, on line 5—5, Fig. 3.

Fig. 6 is a sectional elevation on line 6—6, Fig. 2.

Fig. 7 is a rear elevation, partly in section, on line 7—7, Fig. 6.

The hair treating device 10, as illustrated in the drawings, is in the form of a casing provided with a cover or movable section 11 adapted to be opened for placing a tress or lock of hair therein and providing, when the cover is closed, a treating chamber in which the hair may be treated or processed for one or another purpose. For instance, as disclosed in the copending appli-

cation for United States patent filed July 11, 1941, Serial No. 401,928 by Albert Shelby and Carl F. Hilgeman, the device is equipped with means for stretching or placing the hair under tension while it is subjected to the softening or modifying action of steam or hot vapor in the treating chamber of the casing, for the purpose of straightening curly or kinky hair. In such uses of the device, the tress of hair being treated is preferably gripped close to the head and held to prevent any pull on the hair from being transmitted to the head and for this purpose protruding lips 11a may be provided at the end of the device nearest to the head between which the tress enters the casing and which clamp the root end of the tress. When the hair is thus gripped, the device should be held immovable to prevent pulling the hair, with consequent discomfort to the subject. The treating device may be used for other desired treatments of the hair, and it may be of other constructions adapting it for performing one or another kind of treatment of the hair.

For thus stationarily supporting the treating device or casing 10 in different desired adjusted positions, it is mounted on a stand or support which is preferably constructed as illustrated in the drawings, and comprises a base 12, a standard or post 13 which is vertically adjustable on the base 12, a swivel head 14 which is angularly adjustable in a horizontal plane on the upper end of the post 13, a bracket or member 15 which is pivoted to the swivel head to swing about one horizontal axis and on which the device or casing 10 is pivoted to swing about another horizontal axis disposed at an angle to the first horizontal axis.

The post 13 has a vertical lower portion which is arranged to slide vertically in an upright, tubular column or portion 16 of the base and is adjusted vertically therein, preferably by mechanism comprising a hand crank 17 secured to the shaft of a worm 18 which meshes with a worm wheel 19 on a shaft 20 to which is fixed a pinion that meshes with a toothed rack 21 on the vertical portion of the post 13. By turning the crank in one direction or the other, the standard can be raised or lowered in the base and will be held at the adjusted elevation by reason of the toothed engagement of the worm wheel with the worm. Preferably, the post 13 has a laterally and upwardly inclined upper portion with an enlarged upper end, on which the swivel head 14 is mounted by means of a vertical stud or shaft 22 fixed to the swivel head and arranged to turn in a ver-

tical bearing hole 23 in the upper end of the post 13. Fixed to the lower portion of shaft 22 is a worm wheel 24 which is located in a chamber or cavity in the post enlargement 13 and meshes with a worm 25. This worm is housed in the cavity in the post enlargement and is fixed on a shaft 26 which is journalled in suitable bearings in the post enlargement and provided at one end with a hand wheel 27 for rotating the worm. The swivel head can be rotatably adjusted in either direction about the axis of shaft 22 by turning the hand wheel in one or the other direction, and the swivel head will be held stationary in the position to which it is adjusted by the toothed engagement of the worm wheel with the worm.

The pivot bracket 15, as shown, is formed with a horizontal bearing sleeve or portion 30 from which a lug or part 31 projects downwardly and is pivoted to the swivel head 14 by a pivot or pin 32, preferably secured in holes in lugs 33 and 34 rising from the swivel head at opposite sides of the lug 31 of the pivot bracket. A pivot or pin 35 passes through and bears in the bracket sleeve 30 and in holes in hinge brackets 36 and 36a which may be bolted or otherwise suitably secured to the bottom of the casing or device 10 and depend therefrom at opposite ends of sleeve 30. The pivot 35 may turn in the sleeve 30 and be fixed to the hinge brackets 36, 36a, as shown, or it may be secured in the sleeve and the hinge brackets 36 and 36a permitted to turn on the ends of the pivot. The two pivots 32 and 35 are disposed horizontally at an angle, preferably a right angle, to each other, so that the pivot bracket can swing or tilt about the axis of pivot 32 in one vertical plane while the device 10 can swing or tilt about the axis of the other pivot 35 in a vertical plane which is at an angle or perpendicular to the first mentioned vertical plane.

Suitably secured to lug 31 of the pivot bracket 15 by screws or otherwise, is a worm gear segment 37 which meshes with a worm 38 secured to a shaft 39 which is journalled in suitable bearings on the swivel head 14 at opposite ends of the worm, and to one end of which shaft is fixed a hand wheel 40 for turning the worm. The worm 38 is located within a cavity or chamber 41 in the swivel head which serves as a casing or housing for the worm gearing, and is adapted to contain a lubricant for the gearing and shaft bearings. By means of the hand wheel 40, the pivot bracket 15 can be tilted or swung in one or the other direction about the axis of the pivot 32.

A worm gear segment 43 is suitably secured by screws or otherwise to one of the hinge brackets, as 36a, which are secured to the casing or device 10. This gear segment meshes with a worm 44 fixed to a worm shaft 45 which is suitably journalled at its opposite ends in a bearing arm or part 46 projecting from the sleeve 30 of the pivot bracket 15. Bearing arm 46 has a cavity or chamber within which the worm is housed or protected and which may serve as a container for lubricant for the worm and worm shaft bearings. By turning a hand wheel 47, secured to one end of the worm shaft 45, in one direction or the other, the device 10 can be tilted up or down in a vertical plane extending longitudinally of the device, while by turning the hand wheel 40, the device can be tilted sidewise to one or the other side in a vertical plane extending transversely of the device.

Suitable stop means may be provided for limiting the longitudinal and transverse tilting adjustments of the treating device 10 to desired

ranges of movement. The means for this purpose, as illustrated in the drawings, includes a stop 50 in the form of a loop clamped on bearing arm 46 of the pivot bracket 15 and against the upper end of which the worm segment 43 is adapted to strike to limit the downward tilting movement of the front end of the treating device. Stop pieces 51 suitably secured to the lug 33 of the pivot bracket 15, limit sidewise tilting movement of the device in either direction by engagement of the lug 31 with one or the other of these stop pieces.

With the apparatus constructed as shown and described, the post 13 can be raised or lowered by turning the hand crank 17 to place the treating device or casing 10 at the elevation of the subject's head, and the treating device or casing can then be swung horizontally either to the right or left, and the front end of the device tilted or tipped upwardly or downwardly and also tilted sidewise to either side by appropriately turning the worm operating wheels 27, 40 and 47. Thus, the device can be adjusted to whatever position may be necessary to most conveniently and efficiently operate upon or treat a tress of hair on any portion of the subject's head, and the device will be held stationary and in the adjusted position, whatever that may be. Any desired adjustment can be quickly and easily effected by the operator, by the use of only one hand.

I claim:

1. An apparatus for stationarily supporting a hair treating device in different adjusted positions, comprising a supporting standard, a swivel head movable angularly on said standard about a vertical axis, worm gearing for so adjusting said swivel head, and a universal connection supporting said treating device from said swivel head and comprising two pivot joints arranged with their axes horizontal and at an angle to each other, whereby said device is adapted to swing in vertical planes extending longitudinally and transversely of said device, and a worm gearing for effecting each of said pivotal adjustments.

2. An apparatus for stationarily supporting a hair treating device in different adjusted positions, comprising a supporting standard, a swivel head movable angularly on said standard about a vertical axis, a pivot bracket connected to said swivel head to pivot about a horizontal axis, and a hinge connection between said device and said pivot bracket on which said device is arranged to pivot about a horizontal axis disposed at an angle to said first mentioned horizontal axis, and a worm adjusting mechanism for effecting each of said adjustments.

3. An apparatus for stationarily supporting a hair treating device in different adjusted positions, comprising a supporting standard, a base, means for adjusting said standard to different elevations on said base, a swivel head movable angularly on said standard about a vertical axis, worm gearing for so adjusting said swivel head, and a universal connection supporting said treating device from said swivel head and comprising two pivot joints arranged with their axes horizontal and at an angle to each other, whereby said device is adapted to swing in vertical planes extending longitudinally and transversely of the device, and a worm gearing for effecting each of said pivotal adjustments.

4. An apparatus for stationarily supporting a hair treating device in different adjusted positions, comprising a supporting standard, a swivel

head movable angularly on said standard about a vertical axis, worm gearing for so adjusting said swivel head, a pivot bracket having a pivot connection with said device and a pivot connection with said swivel head, said pivot connections having pivotal axes disposed horizontally perpendicularly to each other, and worm adjusting gearings one for tilting said device on one connection and the other for tilting said pivot bracket on said other pivot connection.

5. An apparatus for stationarily supporting a hair treating device in different adjusted positions, comprising a supporting standard, a swivel head movable angularly on said standard about a vertical axis, and a universal connection supporting said treating device from said swivel head and comprising two pivot joints arranged with their axes horizontal and at an angle to each other, whereby said device is adapted to swing in vertical planes extending longitudinally and transversely of said device, and adjusting and

holding mechanisms for adjusting said swivel head and for adjusting said treating device and holding it in different adjustments about said two pivots.

5. 6. An apparatus for stationarily supporting a hair treating device in different adjusted positions, comprising a supporting standard, a swivel head movable angularly on said standard about a vertical axis, a pivot bracket having a pivot connection with said swivel head and with which said device has a pivot connection, the axes of said pivot connections being disposed at an angle to each other, a worm gear segment on said bracket concentric with the first mentioned pivot connection, a rotatable worm on said swivel head meshing with said gear segment, a second worm gear segment, fixed to said device concentric with said other pivot connection, and a rotatable worm on said pivot bracket meshing with said second gear segment.

FREDERICK J. CLARK.
